UNITED STATES PATENT OFFICE

2,460,821

OSCILLATING VANE ROTARY PUMP

Joseph O. Hamren, Minneapolis, Minn.

Application September 3, 1942, Serial No. 457,129

4 Claims. (Cl. 103—140)

1

This invention relates to a pump for pumping fluids, particularly liquids, and to a pump of the continuous discharge and rotary type.

It is an object of this invention to provide a pump of the rotary type which shall be very efficient, and one in which the discharge can be regulated to vary the torque effort of the pump.

It is a further object of the invention to provide a pump having a stator in the form of a cam having a chamber therein with which the inlet of the pump communicates, said cam having openings at opposite sides thereof and a rotor comprising a plurality of circumferentially arranged swinging vanes having free ends with surfaces adapted to rotate in engagement with said cam, said vanes being closely surrounded by a casing having a discharge opening therethrough together with means for rotating said rotor with the free ends of said vanes advancing.

It is another object of the invention to provide a pump as set forth in the preceding paragraph together with means for variably restricting said openings through said cam member to vary the torque or rotative effort or turning moment of said pump.

It is more specifically an object of the invention to provide a pump comprising an outer casing, a shaft journalled in and extending through said casing, said casing having an inlet chamber at one end thereof, an inner casing secured in said casing having a cylindrical inner wall, a cam member within said inner casing having a chamber therein and extending about said shaft, said cam member having openings at opposite sides thereof, a rotor secured to said shaft having a disk-like portion extending to the wall of said inner casing, a multiplicity of swinging vanes carried on said disk-like portion having free ends with curved surfaces adapted to rotate in engagement with said cam and having hub portions substantially engaging the wall of said inner casing, said chamber within said cam communicating with said inlet chamber of said first mentioned casing, said first mentioned casing forming a chamber about said inner casing and said inner casing having openings equal in number to the openings through said cam leading to said last mentioned chamber together with means for rotating said rotor with the free ends of said vanes advancing.

It is still further an object of the invention to provide a pump as set forth in the preceding paragraph with movable members in the openings through said cam member and means operable from the outer side of said first mentioned casing for moving said members to variably restrict said openings.

It is also an object of the invention to provide a pump comprising a casing, a shaft journalled in and extending through said casing, an inner

5

2

casing secured within said casing, said first mentioned casing forming a chamber about said inner casing and having inlet chambers at the end portions thereof, said inner casing having an inner cylindrical wall, cam members secured in said inner casing having chambers therein extending about said shaft with openings at opposite sides thereof, said chambers communicating with said inlet chambers, a rotor secured to said shaft having a central disk-like portion extending between said cams to the wall of said inner casing, a multiplicity of pins carried in the outer portion of said disk-like portion and projecting from opposite sides thereof parallel to said shaft, a swinging vane mounted on each of said pins having a free end with a convex surface adapted to ride on its respective cam in the rotation of said rotor, said inner casing having discharge openings therethrough equal in number to the number of openings through said cams and means for rotating said rotor with the free ends of said vanes advancing.

It is a further object of the invention to provide a pump such as set forth in the preceding paragraph with movable members in the openings through said cam members and means operable from the outer side of said first mentioned casing for moving said last mentioned members to variably restrict said openings through said cam members to vary the torque or rotative effort or turning moment of said pump.

These and other objects and advantages of the invention will be fully set forth in the following description made in connection with the accompanying drawings in which like reference characters refer to similar parts throughout the several views and in which:

Fig. 1 is a view for the most part in central vertical section through said pump and a portion of a transmission unit connected thereto, the other portion of said unit being shown in side elevation;

Fig. 2 is a vertical section taken on line 2—2 of Fig. 1 as indicated by the arrows;

Fig. 3 is a partial vertical section taken on line 3—3 of Fig. 2; and

Fig. 4 is a vertical section taken on line 4—4 of Fig. 1 as indicated by the arrows.

Referring to the drawings, a pump is shown comprising an outer casing 10 having end members 10a and 10b having flanges secured to a central and generally cylindrical portion 10c. Portions 10a and 10b have secured therein ball bearings 11 in which is journalled a shaft 12 extending through said casing. An oil ring or packing member 13 is disposed at the outer end of each of the bearings 11 and end portions 10a and 10b are provided with recesses adapted to receive packing material 14 extending about shaft 12, said material being held in place by end plates 15 dis-

65

posed in each of the end members 10a and 10b and secured by screws 16 having heads countersunk in said plates. End members 10a and 10b are secured to the central portion 10c by circumferentially spaced headed bolts 17 and said end members have chambers 10d and 10e therein which constitute the inlet chambers for said pump. It will be noted that end members 10a and 10b have openings 10f leading from chambers 10d and 10e inwardly. Casing 10 at opposite sides has 10 bosses 10g and 10h to which are secured connecting members 18 and 19 forming the discharge members or conduits into which the discharge conduits will be suitably connected. Passages 10h and 10i extend through bosses 10g, said passages tapering inwardly.

End members 10a and 10b are rabbeted at their inner ends to form flanges about which extends the cylindrical wall 20a of an inner casing 20, said member 20a being secured by dowel pins 21. End plates 20b of said inner casing which are of annular form, fit within member 20a and are secured thereto by the circumferentially spaced screws 22, having their ends countersunk in member 20a. Member 20a has a cylindrical inner wall. A rotor 24 has a hub secured to shaft 12 by a plurality of circumferentially spaced keys 25 and a disk-like portion 24a extends centrally from said rotor to the inner wall of member 20a. Spacer members 29 are disposed on shaft 12 at each end of the hub of rotor 24 and extend to bearings 11. It will be noted that end members 20b have central openings, said members 29 being disposed within said openings and spaced from the sides thereof. Cam members 27 are provided, there being a cam member secured to each end plate 20b so that they are disposed at each side of disk-like portion 24a and in engagement with the latter. End members 20b are recessed to receive flanges on cam members 27 and said cam members are respectively secured to said end plates by the headed bolts 28 having their heads countersunk in said cam members. Cam members 27 have chambers therein, which chambers are open at their outer ends, the openings in said outer ends being aligned with the openings in said end plates 20b and the openings in the latter communicate with the openings or passages 10f so that there is a passage from the inlet chambers 10d and 10e respectively into the cams 27. Cam members 27 have openings 27a at opposite sides thereof and while the number of these openings may be varied, in the embodiment of the invention illustrated said openings are shown as four in number. It will be noted as shown in Fig. 4, that said cams have outer surfaces 27b which are eccentric to the axis of shaft 12. The disk-like portion 24a has secured therein adjacent its periphery a multiplicity of pins 30. Pins 30 are circumferentially spaced and project at opposite sides of portion 24a having their axes parallel to the axis of shaft 12 and the pins at opposite sides of disk 24a are arranged in staggered relation. Pins 30 have their ends threaded into portion 24a, there also being an unthreaded portion disposed in a bore in said portion 24a. Pins 30 also have collars 30a thereon engaging the side of portion 24a. Journalled on each pin 30 including the portion 30a, is a vane 31. Each vane has a hub portion extending about pin 30, which hub portion is in substantial engagement with the inner wall of member 20a. Said vanes have free ends and these are provided with convex surfaces 31a which are adapted to rotate in

engagement with the periphery of cam members 27. Each vane also has a recessed or concave portion 31b which fits over the hub of the adjacent vane. Each pin 30 is secured at its end opposite portion 24a to a ring 32 by circumferentially spaced screws 33, said rings 32 being disposed in and adapted to rotate in annular grooves in the end plates 20b. The openings 27a in cam members 27 are formed in part of semi-cylindrical form and valves 35 are disposed in said openings extending lengthwise of cam members 27. Each plate or valve 35 is carried on a shaft 36 and is secured thereto by the spaced screws 34 as shown in Fig. 3. Shafts 36 are journalled in the end members 20b and at the outer side of said end members have secured thereto arms 37. While these arms may be secured in any manner, they are illustrated as secured by pins 38a. Arms 37 incline outwardly through the passages 10f and at their outer ends are bifurcated to embrace a ring 38 to which they are pivotally connected by a headed pin 39 held in place by a cotter pin 40. Ring 38 has inwardly projecting arms 38c adapted to engage and ride upon the hub of end plate 10b which contains the bearing 11. The ring 38 is provided at one portion, shown as the upper portion thereof, with rack teeth 38b and these are engaged by a pinion or teeth 41a formed on the lower end of a shaft 41 which extends upwardly and is journalled in the end plate of casing 10. It will be understood that there are two rings 38 and one shaft 41 is journalled in end plate 10a and the other shaft 41 is journalled in end plate 10b. End plate 10a is recessed to receive a collar 42 having a conical recess in its upper end and packing material 43 is disposed about a reduced portion of shaft 41 and engaged at its upper end by a gland 44, the top of which contacts an arm 45 secured to shaft 41 and held in place by a castle nut 46 threaded on the upper end of shaft 41. A similar construction and arrangement of the same parts is shown for shaft 41 in end plate 10b, which shaft has an arm 47 secured thereto. It will be seen that by rotating the arms 45 and 47 that shaft 41 will be rotated and rings 38 will be moved about their axes to swing arms 37, thus turning shafts 36 and moving plates 35 about longitudinal axes to more or less restrict the openings 27a. The outer ends of shafts 36 are also journalled in the hubs of the end plates 10a and 10b, said hubs being provided with circumferentially spaced bosses 10j bored to receive said shafts.

The end members 10a and 10b are provided with circumferentially spaced holes or passages 10k which communicate with the chambers 10d and 10e respectively. A sleeve 50 is provided which closely fits on and is rotatable on the outer cylindrical surface of casing portion 20a. Said sleeve has flanges 50a at each end and these fit against the inner sides of end members 10a and 10b respectively. It will be noted that the outer casing portion 10c extends about sleeve 50 and forms a chamber 10m thereabout. Flanges 50a are provided with circumferentially spaced holes or passages 50b adapted to be brought into and out of register with passages or holes 10k. The inner casing member 20a has openings or passages 20d therethrough, one being shown for each of the cam openings 27a and openings 20d are thus four in number and circumferentially spaced equally about member 20a. The sleeve 50 has openings or passages 50d registering with the passages 20d and of sufficient

length circumferentially so that they will always register with passages 20d in the rotation or oscillation of said sleeve. Sleeve 50 is adapted to be oscillated and for this purpose has secured thereto at its outer side in chamber 10m a rack 51. Rack 51 is engaged by a pinion 52 secured to the inner end of a shaft 53 extending outwardly through a boss 10n on casing member 10c to the outer end of which is secured an arm 54. Arm 54 as well as arms 45 and 47, are shown as having bifurcated and transversely bored outer ends adapted to be connected to a suitable control member or lever. Boss 10n is bored and an oil packing ring 55 is disposed at the bottom of said bore about shaft 53, the same being surmounted by a collar 56 having a conical upper surface and packing material 57 is disposed in said member 56 about shaft 53 and is engaged by a gland member 58 which is in turn engaged at its upper end by the hub of arm 54. A nut 59 shown as of the castle type is shown as threaded on the upper end of shaft 53 and holds arm 54 in place. Sleeve 50 has secured to its end flange in any suitable manner as by welding a plate 60 movable in contact with the inner cylindrical wall of portion 10c and adapted to be moved over the inner end of passage 10h to more or less close said passage. A plate 61 at the opposite side of member 10c is also secured to sleeve 50 as is plate 60 and has an opening or slot 61a at its central portion. Plate 61 is arranged to be moved more or less over the inner end of passage 10i as sleeve 50 is moved to more or less restrict passage 10i.

The casing 10 has an inlet passage or chamber 10p shown as at its lower end and this communicates through the passages 10q at the ends thereof with the inlet chambers 10d and 10e respectively. The chamber 10p is shown as in communication with a passage 10r formed in a portion 65a of a casing member 65 of a transmission unit. Said casing 65 is illustrated as secured to the casing 10 and specifically to member 10c by the spaced headed and nutted bolts 66. The pump and the transmission unit in casing 65 thus constitute one structural assembly. It will of course, be understood that the pump could be separate and used for other purposes than that of supplying a fluid or liquid to said transmission unit. Said transmission unit is of the type disclosed and claimed in applicant's co-pending application S. N. 376,626, filed January 31, 1941, now issued as Patent No. 2,404,229, granted July 16, 1946 and the same comprises a cam member 70 and vanes 71 carried on a rotor, which rotor is disposed within the inner casing 72. It is believed that further description of the transmission unit will be unnecessary.

In operation, fluid or liquid will be supplied to the inlet chamber 10p in any suitable manner as from the return passage 10r from said transmission unit and this liquid will pass through passages 10q to the inlet chambers 10d and 10e. The liquid will then pass through passages 10f and through the inner openings of end plates 20b and cams 27 to the inner side of cams 27. Shaft 12 will be driven in any suitable manner and this will rotate the rotor 28. The rotor is rotated in a direction so that the free ends of the vanes 31 will advance, which direction is indicated by the arrows in Fig. 4. As the vanes are carried about, their surfaces 31a ride on the cam surfaces 27b and the position of the vanes is changed as shown in Fig. 4. The vanes pass the openings 27a and as shown at the upper left hand corner of Fig. 4,

it will be seen that the chamber between the periphery of the cam and the two vanes in contact is quite small. As the rotor advances the positions of the vanes change so that the chamber between the vanes is enlarged. This causes a suction which draws the liquid from the inner side of cam members 27 through openings 27a into the chamber between said cam members and casing 20. As the rotor continues to revolve, the enlarged chamber between vanes 31 is again reduced as the vanes pass the openings 20d and the fluid is forced out through the openings 20d and through openings 50d in sleeve 50 into the chamber between sleeve 50 and the outer casing 10. From this chamber it passes through passages 10h or 10i to discharge members 18 and 19. With the members or plates 35 in the position shown in Fig. 4, the pump can deliver its maximum of fluid or liquid. The amount of liquid handled can be reduced by moving the plates 35 and this can be done by oscillating arms 45 and 47 to oscillate shafts 41 causing the toothed portions 41a to rotate ring 38 and swing arms 37, thus oscillating shafts 36 and plates 35. By reducing the amount of fluid or liquid passing through the pump or the cam members 27 the torque effort of the pump can be increased. The sleeve 50 can be rotated or oscillated on casing member 20a by swinging arm 54. This rotates shaft 53 and pinion 52 acts on rack 51 causing rotation of sleeve 50. When the pump is delivering fluid the openings or passages 10k and 50b are out of alignment as indicated in Fig. 4. At this time ordinarily one of the passages 10h and 10i is closed by its respective plate 60 or 61. As stated, plates 60 and 61 are connected to sleeve 50 and when plate 60 as shown in Fig. 4, moves in a clockwise direction it will close passage 10h and the opening 61a in plate 61 will come into register with passage 10i and open the latter. With the construction of plates 60 and 61 shown both passages 10i and 10h may be partly open. Fluid could then be discharged through both outlets 18 and 19. The sleeve 50 can be oscillated to bring passages 50b and 10k into register and at this time passages 10h and 10i are both closed. The fluid would then merely be bypassed from chamber 10m through passages 50b and 10k into the inlet chambers 10e and 10d and would be moved again through the cam members 27 and discharged through openings 20d and 50d into chamber 10m. The fluid would thus circulate idly in the pump.

From the above description it will be seen that I have provided a simple and efficient rotary pump and one in which the driving shaft is concentric with the wall of the pump casing. As stated, the change in position of vanes 31 causes a change in the volume of the chambers therebetween giving the pumping action and the pumping action may also be increased by a centrifugal action of vanes 31 as the rotor rotates at high speed. The pump is capable of pumping any kind of fluid and will be particularly useful in pumping fluid such as oil. The structure is very compact and easily maintained. There will be an oil film on the inner wall of casing portion 20a and also on cam member 27 so that with these portions made of hard material there will be little wear. It will be obvious that the device will have a high degree of utility for the purpose intended.

It will of course, be understood that various changes may be made in the form, details, arrangement and proportions of the parts, without departing from the scope of applicant's invention.

tion, which generally stated, consists in a device capable of carrying out the objects above set forth, in the parts and combinations of parts disclosed and defined in the appended claims.

What is claimed is:

1. A pump having in combination, a casing having an inlet chamber therein, a shaft journaled in and extending through said casing, a cam member surrounding said shaft and having a chamber therein communicating with said inlet chamber and adapted to receive fluid therefrom, a rotor in said casing secured to said shaft and comprising a plurality of swinging vanes carried thereon, each vane having a free end with a surface adapted to rotate in engagement with said cam member, said cam member having a plurality of equally and circumferentially spaced openings therethrough; an inner casing closely surrounding said vanes and forming a chamber about said cam member adapted to receive fluid through said openings, said first mentioned casing having an outlet chamber extending about said inner casing and adapted to receive fluid therefrom, said inner casing having equally and circumferentially spaced discharge openings into said outlet chamber equal in number to the openings through said cam member, a valve member disposed in each of said openings through said cam member adapted to be oscillated for variably restricting said openings through said cam member to vary the torque of said pump, pivot members secured to said valve members, arms secured to said pivot members, a ring secured to said arms and rotatable for swinging said arms and means at the outer side of said first mentioned casing for rotating said ring.

2. A pump having in combination, a casing having inlet chambers therein at its ends, a shaft journaled in and extending through said casing, a second casing secured in said first mentioned casing and spaced from the wall of said first mentioned casing to form a discharge chamber thereabout, a rotor in said second casing having a hub secured to said shaft and having a disk-like portion extending to the wall of said second casing, a cam member at each side of said disk-like portion, each cam member having a chamber therein surrounding said hub, communicating with said inlet chambers respectively and having a plurality of circumferentially and equally spaced openings therethrough from said chamber therein into said second casing, a plurality of swinging vanes carried by said disk-like portion, said vanes being equally and circumferentially spaced at each side of said disk-like portion and having free ends with convex surfaces adapted to rotate in engagement with said cam members respectively, said second casing having equally and circumferentially spaced openings equal in number to the openings in each of said cam members leading to said discharge chamber, a valve member disposed in each of said openings through said cam members and adapted to be oscillated for variably restricting said openings through said cam members to vary the torque of said pump, pivot members secured to said valve members, arms secured to said pivot members, a ring at each end of said casing secured to said arms connected to the valve members of each cam member respectively, said rings being rotatable for swinging said arms and moving said valve members and means at the outer side of said first mentioned casing for rotating said rings.

3. A pump having in combination, a casing

journaled in and extending through said casing, a second casing secured in said first mentioned casing and spaced from the wall of said first mentioned casing to form a discharge chamber between said casings, a rotor in said second casing having a hub secured to said shaft and having a disk-like portion extending to the wall of said second casing, a cam member at each side of said disk-like portion, each cam member having a chamber therein surrounding said hub, communicating with said inlet chambers respectively and having a plurality of circumferentially and equally spaced openings therethrough from said chamber therein into said second casing, a plurality of swinging vanes carried by said disk-like portion, said vanes being equally and circumferentially spaced at each side of said disk-like portion and having free ends with convex surfaces adapted to rotate in engagement with the periphery of said cam members respectively, said second casing having equally and circumferentially spaced openings equal in number to the openings in each of said cam members leading to said discharge chamber, a valve disposed in each of said openings in said cam members and adapted to be oscillated for variably restricting said last mentioned openings, pivot members secured to said valve members, arms secured to said pivot members, a ring at each end of said casing secured to said arms connected to the valve members of each cam member respectively, said rings being rotatable for swinging said arms, said rings having teeth formed thereon, a pinion respectively meshing with the teeth on each of said rings, shafts secured to said pinions respectively and journaled in said first mentioned casing and extending to the outer side thereof and means secured to said last mentioned shafts respectively for turning the same and said pinions and rings 40 and operating said valves to vary the torque effort of said pump.

4. A pump having in combination, a casing, a shaft journaled in and extending through said casing, a cam member surrounding said shaft and having a chamber therein adapted to receive fluid, a rotor in said casing secured to said shaft and comprising a plurality of swinging vanes carried thereon, each vane having a free end with a surface adapted to rotate in engagement with said cam, said cam member having openings therethrough at opposite sides thereof, a second casing closely surrounding said vanes and having circumferentially spaced discharge openings therethrough said second casing forming a chamber about said cam member adapted to receive fluid through said openings in said cam member, said first mentioned casing having an outlet chamber extending about said second casing to form a discharge chamber adapted to receive fluid through said discharge openings and having an inlet chamber communicating with the chamber in said cam member, a valve member disposed in each of said openings through said cam member adapted to be oscillated for variably restricting said openings through said cam member, pivot members secured to said valve members, arms respectively secured to said pivot members, a ring at the end of said casing secured to said arms, said ring being rotatable for swinging said arms and moving said valve members, said ring having teeth formed thereon, a pinion meshing with the teeth on said ring, a shaft secured to said pinion and extending to the outer side of said first mentioned casing and means secured to said last mentioned shaft for rotating the same

and said pinion, rotating said ring and operating said valves to vary the torque of said pump.
